United States Patent Office

Des. 219,367
Patented Dec. 8, 1970

219,367

BOTTLE

Dan Lewis, Jr., Champaign, Ill., assignor to National Distillers and Chemical Corporation, New York, N.Y., a corporation of Virginia

Filed June 26, 1969, Ser. No. 17,897

Term of patent 14 years

Int. Cl. D9—01

U.S. Cl. D9—46

FIG. 1.

FIG. 2.

FIG. 1 is a side elevational view of a bottle showing my new design;

FIG. 2 is a side elevational view looking from the right of FIG. 1;

FIG. 3 is a top plan view;

FIG. 4 is an elevational view looking from the side opposite that of FIG. 1;

FIG. 5 is a top plan view of another embodiment of my new design having a modified finish and showing the handle in the down position;

FIG. 6 is a fragmentary side elevational view showing the upper portion of the bottle of FIG. 5, it being understood that the portions not shown are the same in appearance as the respective portions of the bottle of FIGS. 1, 2, 3 and 4; and

FIG. 7 is a side elevational view looking from the right of FIG. 6.

I claim:

The ornamental design for a bottle, as shown and described.
